Atty.

UNITED STATES PATENT OFFICE.

EDWARD F. CULLEN, OF BROOKLINE, MASSACHUSETTS.

DISPLAY BOX.

Application filed July 29, 1924. Serial No. 728,820.

To all whom it may concern:

Be it known that I, EDWARD F. CULLEN, a citizen of the United States of America, residing at Brookline, in the county of Norfolk and State of Massachusetts, have invented new and useful Improvements in Display Boxes, of which the following is a specification.

This invention relates to display boxes or containers adapted for holding crackers, cookies and the like, in stores, so that the contents of the container are encased and protected while being visible for inspection by prospective customers.

15 It has been heretofore customary to provide square containers of sheet metal for this purpose that have been provided with a square sheet metal cover flanged to fit down closely upon the top of the box or container, 20 this cover having its major interior portion cut away and provided with an inserted glass pane through which the contents of the box are exposed.

Thus this type of square cover, with its 25 transparent glass insert, has become a standard article in stores handling cookies and crackers, and the merchant usually has on hand a considerable number of such covers. It is however, often convenient, and more 30 economical for the manufacturer to supply his product in larger boxes which are often made of wood, paper board, or the like, and a considerable part of the product has come to be packed in oblong wooden boxes of a 35 width corresponding to that of the standard metal containers, before mentioned, and of twice the length of such metal containers.

There has heretofore been no practicable and economical way of displaying attractively the contents of such wooden or paper-board boxes without removing the contents therefrom and putting them into the square metal containers, which of course requires time and disturbs the original packing of 45 the crackers.

The object of the present invention is to provide means whereby the standard square metal box cover above mentioned, with its glass insert, may be fitted and applied to 50 such oblong wooden or like boxes so as to fit the same closely and present an attractive appearance for display of the goods. To this end I produce the oblong box as usual, but provide in the top portion of the sides 55 thereof midway of its ends, slots or channels

adapted to receive the flanges of two standard square metal covers which are fitted and applied to the respective end portions of the wooden box, and which together make a 60 complete cover therefor.

The foregoing and other objects and advantages of the invention will more fully appear from the following detailed description taken in connection with the accompanying drawings, and the distinctive features of novelty will be pointed out in the 65 appended claims.

Referring to the drawings—

Figure 1 is a plan view of a box equipped with the invention, and showing one of the 70 metal cover units applied to one end of the box;

Figure 2 is a side elevation of the box with both cover units applied thereto; and

Figure 3 is a transverse section on line 75 3-3 of Fig. 2.

10 indicates an oblong box which may be of wood, paperboard, or the like, of suitable depth, and of a length illustratively shown as twice the width thereof, although in a 80 broader aspect of the invention, the length might be any exact multiple of the width.

In accordance with my invention, the longitudinal sides of the box are channeled or slotted midway of their length from the top 85 downward, as indicated at 11, 12, to a depth sufficient to receive the down-turned flanges 13^a of square cover units 13, these channels or slots being of sufficient width to receive the adjacent flanges of two such cover units 90 which are applied and fitted to the two end portions of the box, as seen in Fig. 2. These cover units 13 are of the usual standard type found in stores handling crackers, biscuits and cookies, and comprise a square sheet 95 metal frame 13^b from which the flange or shroud portions 13^a depend, such frame having its major interior portion cut out as indicated at 13^c and a glass pane 14 applied thereto. Thus these standard transparent 100 metal cover units 13 are adapted to be instantly and easily applied to the wooden or like boxes 10 upon removal of the original wooden or like cover therefrom, and when so applied, two of these metal cover units make 105 a complete cover and closure for the box while presenting an attractive transparent front for the display of the goods.

I am aware that the invention may be embodied in other specific forms without de- 110

parting from the spirit or essential attributes thereof, and I therefore desire the present embodiment to be considered in all respects as illustrative and not restrictive, 5 reference being had to the appended claims rather than to the foregoing description to indicate the scope of the invention.

Having described my invention, what I claim as new and desire to secure by Letters Patent is:—

1. An oblong box having the longitudinal sides thereof slotted intermediate the length thereof from the top downward, and flanged metallic cover units fitted to the respective 15 end portions of said box and having the flanges at the inner sides of such cover units received in such slots.

2. An oblong, rectangular box of wood or the like having the longitudinal sides thereof slotted from the top downwardly midway of their length, and flanged metallic cover units applied to the respective end portions of such box with the flanges at the inner sides of such units fitting in such slots, said cover units having their major interior portions cut away and fitted with transparent panes. 20 25

In testimony whereof I affix my signature in presence of two witnesses.

EDWARD F. CULLEN.
